(57) **CLAIM**

The ornamental design for a TV mounted shelf, as shown and
described.

DESCRIPTION

FIG. 1. is a front perspective view of my TV mounted shelf;
FIG. 2. is a front view thereof;
FIG. 3. is a rear elevation view thereof;
FIG. 4. is a left side view thereof, the right side view being a
mirror image thereof;
FIG. 5. is a top view thereof;
FIG. 6. is a bottom view thereof; and,
FIG. 7 is a rear perspective view of the TV mounted shelf
shown with a TV in broken lines.
The broken lines showing a TV are for the purpose of illus-
trating the environment of the article and form no part of the
claimed design.
